UNITED STATES PATENT OFFICE.

CLAUDE BETHEL, OF WILKINSBURG, AND THOMAS S. SCOTT, OF PITTSBURGH, PENNSYLVANIA, ASSIGNORS TO WESTINGHOUSE ELECTRIC AND MANUFACTURING COMPANY, A CORPORATION OF PENNSYLVANIA.

CURRENT-COLLECTING DEVICE.

Application filed July 5, 1922. Serial No. 572,860.

To all whom it may concern:

Be it known that we, CLAUDE BETHEL, a citizen of the United States, and a resident of Wilkinsburg, in the county of Allegheny and State of Pennsylvania, and THOMAS S. SCOTT, a citizen of the United States, and a resident of Pittsburgh, in the county of Allegheny and State of Pennsylvania, have invented a new and useful

10 Improvement in Current-Collecting Devices, of which the following is a specification.

Our invention relates to current-collecting devices and it has particular relation to brush holders for electric railway motors, and the like.

One of the objects of our invention is to provide a brush holder, of the character described, which embodies a brush box that is 20 disposed in alignment with a brush pressure device, the box being slidably mounted upon the brush holder in order that it may be quickly and easily withdrawn from between the brush pressure device and the commutator cylinder for convenient access thereto.

Another object of our invention is to provide a device, of the character described, in which a very efficient and compact mechanism is provided for yieldably maintaining 30 the brush box in operative position with respect to the brush pressure device and a rotating contact member, such as a commutator cylinder or a collector ring, during normal operating periods of the machine.

35 A further object of our invention is to provide a current-collecting device of the character set forth, which comprises relatively few parts, is simple and efficient in operation and is of very rugged and substantial construction being adapted to withstand the severe operating conditions incidental to electric railway service.

In the accompanying drawings,

Figure 1 is a view of a portion of a rocker ring of a dynamo-electric machine that is provided with a plurality of brush holders constructed in accordance with our invention, one of the brush holders being illustrated in side elevation and a portion of 45 another being illustrated in vertical longitudinal section;

Fig. 2 is a transverse sectional view

through the rocker ring taken on the line II-II of Fig. 1 and illustrating one of the brush holders in front elevation; and

Fig. 3 is a horizontal sectional view through one of the brush holders and taken on the line III-III of Fig. 2.

Referring to the drawings, a portion of a dynamo-electric machine is illustrated as 60 comprising, in general, a rocker ring 1, which supports a plurality of brush holders 2 and brush members 3 that are carried thereby for cooperation with a commutator cylinder 4.

65 The rocker ring 1 preferably comprises a centrally disposed annular member 5 and a plurality of outer reinforcing ring portions 6, of slightly less diameter, which are secured thereto at intervals and in spaced relation therewith, by means of arms or web portions 7, which are preferably formed integral with the member 5 and the rings 6. The periphery of the member 5 is provided with gear teeth 8 by means of which the 70 ring 1 and the current collecting devices supported thereby may be shifted circumferentially, by any suitable mechanism (not shown), in order to adjust the brush members 3 with respect to the axis of commutation of the machine. The arms 7 are provided with lugs or bosses 9 to which brush-holder-supporting studs 10 are suitably secured.

75 Each of the brush holders 2 comprises a 85 bracket portion 11, which is adapted to be secured to the studs 10 by means of a transversely extending clamping bar 12 and bolts 13. The forward side of the bracket portion 11 of the brush holder is provided 90 with a transversely extending pipe or manifold 14, which is provided with a plurality of tubular projections or cylinders 15 that extend in the direction of the commutating cylinder 4. A piston or plunger 16 is provided in each of the cylinders 15 for engagement with the brush members 3, as will be hereinafter set forth.

95 Each of the cylinders 15 is in communication with the pipe 14, which functions as 100 a header member therefor, and which is provided with a rearwardly extending tubular projection or nipple 17. The projection 17 is permanently secured to the bracket

11 of the brush holder in any preferred manner, and telescopically engages the extremity of a flexible pipe or conduit 18. One extremity of the pipe 18 is secured to the bracket portion 11 of the brush holder by a union or coupling member 19, while the other extremity thereof is secured to a fluid pressure supply pipe 20 in any preferred manner. The supply pipe 20 is preferably disposed concentrically to the rocker ring 1 and is secured thereto by means of transversely extending clamping bars 21 and bolts 22 (Fig. 2).

The bracket portion 11 of the brush holder embodies a flange or wall portion 23, which is provided with a channel or recess 24 and with a plurality of apertures 25 adjacent thereto. A plurality of brush boxes, indicated as a whole at 26, are mounted upon the bracket member 11 and are each provided with a rearwardly extending rod 27, which projects through one of the apertures 25 and into a substantially cylindrical housing 28 that is provided on the rear portion 25 of the flange 23. The rear wall of each of the brush boxes 26 is also provided with a transversely extending rib or flange 29, which is adapted to register with and engage the channel or recess 24 to prevent the brush box from turning about the axis of the rod 27 during the operation of the machine. A spring 30 is mounted upon each of the rods 27, within the housing 28, and is confined between the flange 23 and an adjusting nut 31 that is threaded upon the extremity of the rod 27.

The forward side of each of the brush boxes 26 is preferably provided with a handle 32, by means of which the brush boxes 40 may be separately and independently withdrawn from between the fluid pressure cylinders 15 and the surface of the commutator cylinder 4, and against the action of the springs 30, for the purpose of obtaining 45 access to the brush members 3. During the normal operation of the machine, the springs 30 resiliently maintain the several brush boxes and the brush members 3 that are carried thereby, in operative position with 50 respect to the brush pressure cylinders 15.

While we have illustrated and described our invention as being employed in connection with a fluid pressure device, it will be understood that it is not necessarily limited 55 to such an application, as any suitable brush pressure mechanism, such as the usual brush spring structure, may be employed without departing from the nature and spirit of our invention.

60 We claim as our invention:

1. A current-collecting device comprising a supporting structure, a brush box movably carried thereby and adapted to support a brush member for co-operation with a rotating contact member, a pressure device

carried by said supporting structure and adapted to yieldably maintain said brush member in engagement with said rotating contact member, and means for retaining said brush box in operative position with respect to said pressure device. 70

2. A current-collecting device comprising a supporting structure, a brush box movably carried thereby and adapted to support a brush member for co-operation with a rotating contact member, a pressure device carried by said supporting structure and adapted to yieldably maintain said brush member in engagement with said rotating contact member, and means for resiliently 80 retaining said brush box in operative position with respect to said pressure device. 75

3. A current-collecting device comprising a supporting structure, a brush box movably carried thereby and adapted to support a brush member for co-operation with a rotating contact member, a pressure device carried by said supporting structure and adapted to yieldably maintain said brush member in engagement with said rotating 90 contact member, and a spring member for retaining said brush box in operative position with respect to said pressure device. 85

4. A current-collecting device comprising a supporting structure, a brush pressure device carried thereby, a brush box slidably mounted upon said supporting structure and in alinement with said pressure device, and means for removably maintaining said brush box in operative position with respect to said 100 pressure device. 95

5. A current-collecting device comprising a supporting structure, a brush pressure device carried thereby, a brush box slidably mounted upon said supporting structure and 105 in alinement with said pressure device, and means for resiliently maintaining said brush box in operative position with respect to said pressure device. 100

6. A current-collecting device comprising a supporting structure having an aperture therein, a pressure device carried thereby, a brush box disposed in alinement with said pressure device and provided with an extension adapted to project through said aperture, and a spring carried by said extension for engagement with said supporting structure for maintaining said brush box in operative position with respect to said pressure device and adapted to permit of the withdrawal of said brush box from alinement with said pressure device. 110 115

7. A current-collecting device comprising a bracket member, a brush pressure device carried thereby, and a brush box mounted 120 upon said bracket member for movement into and out of operative position with respect to said pressure device. 125

8. A current-collecting device comprising a bracket member, a brush pressure device 130

carried thereby and a brush box mounted upon said bracket member for movement toward and away from said bracket member.

9. A current-collecting device comprising a bracket member provided with a housing, a brush pressure device carried by said bracket member, a brush box slidably mounted on said bracket member for relative movement with respect thereto, said brush box being provided with a rod adapted to project into said housing, and a spring carried by said rod and disposed within said housing for resiliently maintaining said brush box in operative position with respect to said pressure device.

10. A current-collecting device comprising a bracket member provided with a substantially tubular portion, a brush pressure device carried by said bracket member, a brush box slidably mounted upon said bracket member for relative movement with respect thereto, said brush box being provided with a rod adapted to project into said tubular portion, and a spring carried by said rod and disposed within said tubular portion to resiliently maintain said brush box in operative position with respect to said pressure device.

11. A current-collecting device comprising a bracket member provided with an aperture, a brush pressure device carried by said bracket, a brush box provided with a rod adapted to slidably engage said aperture, a spring carried by said rod and adapted to resiliently maintain said brush box in operative position with respect to said pressure device, and means for adjusting the tension of said spring.

12. A current-collecting device comprising a bracket member provided with an aperture, a brush pressure device carried by said bracket, a brush box provided with a rod adapted to slidably engage said aperture, a spring carried by said rod and adapted to resiliently maintain said brush box in operative position with respect to said pressure device, and means for preventing the

rotation of said brush box about the axis of said rod when in operative position.

13. A current-collecting device comprising a bracket member provided with an aperture extending therethrough and with a channel in one face thereof, a brush pressure device carried by said bracket member, a brush box provided with a rod adapted to slidably engage said aperture, a spring carried by said rod for resiliently maintaining said brush box in operative position with respect to said pressure device, and a rib provided on one face of said brush box and adapted to engage said channel to prevent the movement of said brush box about the axis of said rod.

14. A current-collecting device comprising a bracket member provided with an aperture extending therethrough and having a recess in one face thereof, a brush pressure device carried by said bracket member, a brush box provided with a rod adapted to slidably engage said aperture, a spring carried by said rod for resiliently maintaining said brush box in operative position with respect to said pressure device, and a projection provided on one face of said brush box and adapted to engage said channel to prevent the movement of said brush about the axis of said rod.

15. A current-collecting device comprising a bracket member provided with a channel portion, a brush pressure device carried by said bracket member, and a brush box slidably mounted upon said bracket member for movement into and out of operative position with respect to said pressure device, and provided with a rib portion adapted to engage said channel to prevent the turning movement thereof with respect to said pressure device.

In testimony whereof, we have hereunto subscribed our names this 23rd day of June, 1922.

CLAUDE BETHEL.
THOMAS S. SCOTT.
